UNITED STATES PATENT OFFICE.

EUGEN SCHEIBER AND EMIL KWAYSSER, OF VIENNA, AUSTRIA-HUNGARY.

COMPRESSION STOP-COCK.

SPECIFICATION forming part of Letters Patent No. 729,423, dated May 26, 1903.

Application filed November 3, 1900. Serial No. 35,405. (No model.)

To all whom it may concern:

Be it known that we, EUGEN SCHEIBER and EMIL KWAYSSER, subjects of the Emperor of Austria-Hungary, residing at Vienna, in the

5 Province of Lower Austria, in the Empire of Austria-Hungary, have invented certain new and useful Improvements in Compression Stop-Cocks; and we do hereby declare the following to be a full, clear, and exact description 10 of the invention, such as will enable others skilled in the art to which it appertains to make and use the same, reference being had to the accompanying drawings, and to letters of reference marked thereon, which form a 15 part of this specification.

This invention has relation to compression stop-cocks, and more particularly to such stop-cocks used on bottles containing effervescent or so-called "aerated" liquids, commonly 20 termed "siphon-bottles."

The invention has for its object a construction of dispensing-head for such bottles provided with a compression-cock so organized and arranged to be adapted for operation by 25 the hand which holds the bottle, so that the glass to be filled may be held by the other hand. In order that this may be readily and conveniently accomplished, it is necessary that the device by means of which the compression-cock is operated should be so located 30 as to be in reach of a finger of one hand, while the compression device should be so organized as to immediately and automatically close the discharge-duct in the head the moment 35 the device which operates the compressor is released.

The compression stop-cock which forms the subject of the present invention consists, essentially, of an elastic tube with a closing arrangement which under the action of a spring or the pressure in the vessel containing fluid squeezes part of the pipe, so as to prevent passage of fluid. The arrangement is such that the fluid comes nowhere in contact with 45 metal.

Figure 1 of the accompanying drawings illustrates in longitudinal section the application of this invention to an elastic siphon-head, the squeezing of which is effected by a 50 spring. Fig. 2 shows the squeezing effected by the fluid-pressure. Fig. 3 shows, separately, the closing-lever shown in Fig. 2. Fig.

4 is a section of the cock-casing of the siphon-head shown in Fig. 2. Fig. 5 shows a closing of the siphon-head in which a one-armed lever is employed.

In the head *a*, which is fixed in the usual way on a siphon, is inclosed a tube *b*, of elastic material, which has its one end attached to the outlet-tube *d* and its other end fixed 60 to a nozzle *f* by a nut *e*.

As shown in Fig. 1, the elastic tube is squeezed by a presser *g*, on which bears one arm of a lever *h*, the other arm being urged by a spring *i*, so as to force the presser *g* 65 strongly toward a rounded piece *m*, fixed in the siphon-head.

As shown in Figs. 2 and 5, the pressure in the siphon causes the closure, the lever *h*, which is pivoted at *n*, being acted on by the 70 pressure, so as to squeeze the elastic tube between the two rounded parts at *m*.

On pressing the lever *h* the passage at *m* is opened, allowing the fluid to pass out.

The springs *i* in Figs. 2 and 5 serve only to 75 make the closure at *m* more certain.

As the fluid nowhere comes in contact with the head *a*, it may be made of any material, such as cast metal or sheet metal, shaped and put together in halves without requiring 80 tightness against leakage.

Having thus described our invention, what we claim as new, and desire to secure by Letters Patent, is as follows:

1. The combination with a siphon-bottle, of 85 a dispensing-head comprising a casing provided with a dispensing-nozzle and a flexible impermeable discharge-tube connected to said nozzle and connectible to the siphon-tube, a compressing member intermediate the inlet 90 and outlet of said tube, a two-armed lever mounted on said head one of its arms bearing on said compressing member and a spring acting on the other arm of said lever, for the purpose set forth.

2. The combination with a siphon-bottle, of 95 a dispensing-head, an impermeable flexible tube therein connectible to the siphon-tube, means intermediate the ends of the flexible tube operated by pressure within the bottle 100 to compress said tube, and a hand-operated device acting on the compressing means to relieve the tube of pressure, for the purpose set forth.

3. A stop-cock comprising a flexible tube; a casing therefor comprising a stationary part and a movable part in contact with said tube adapted to be operated to compress said tube by the pressure of liquid in the tube; and means adapted to move the movable part into position to release the pressure on the flexible tube, substantially as herein set forth.
4. The combination with a siphon-bottle, of a dispensing-head comprising a casing provided with a through-passage and a fixed compressing member *m* therein, a flexible impermeable tube *b* in said passage, a dispensing-nozzle fitting into the outer end of said tube and securing it in position, the inner free end of the tube connectible to the siphon-tube, a

spring-actuated companion compressing member coöperating with the fixed member to compress the tube, and means adapted to retract the movable compressing member, mounted and located on the head to be acted on by the hand taking hold of the siphon-bottle, substantially as and for the purpose set forth.

In testimony that we claim the foregoing as our invention we have signed our names in presence of two subscribing witnesses.

EUGEN SCHEIBER.
EMIL KWAYSSER.
